ELECTRODE HOLDER

Henry J. Wagner, Jackson, Mo.

Application December 17, 1946, Serial No. 716,865

5 Claims. (Cl. 219—8)

1

This invention pertains to an improved construction of an electrode holder and more especially has reference to a holder for handling welding electrodes consuming heavy electrical currents.

The primary purposes of my invention are to provide an electrode holder which is capable of handling heavy currents with safety and without undue heating of the implement; which is of relatively light weight and easily manipulated without fatigue by the user; which can readily accommodate a wide variety of sizes of electrodes; and which has a powerful and uniformly applied and maintained clamping action upon the electrodes.

Other ancillary objects reside in constructing a device in accordance with the foregoing objects and which has a normally engaged but manually released gripping arrangement; wherein all of the exposed parts are insulated to minimize dangers of shorts or shocks; wherein the operating mechanism is fully enclosed; and wherein the tool is compact, sturdy and efficient.

These, together with various additional objects which will later become apparent as the following description proceeds, are realized by my device, one embodiment of which has been illustrated, by way of example only, in the accompanying drawings, wherein:

Figure 1 is a perspective view of the invention;

Figure 2 is a vertical sectional view through the device.

Figure 3 is a horizontal sectional view through the invention, being taken substantially upon the line 3—3 of Figure 2.

Figure 4 is a front end elevation of the device as viewed in Figure 1; and

Figures 5 and 6 are perspective views of the upper and lower jaws respectively.

Referring in detail to the drawings, 10 denotes a hollow handle which is preferably constructed of a rigid, tubular exteriorly corrugated or ribbed insulating material, and within which is received the lower or main jaw assembly 12 and an insulated electric cable 14. As shown best in Figure 6, the lower jaw assembly 12 comprises a pair of parallel, spaced side walls 16, integrally united with a longitudinally extending, flat jaw 18 at one end and with a tubular cylinder 20 at the other end, the cylinder being axially bored or recessed as at 22 to detachably receive the end 24 of the cable 14. A series of set screws 26 are provided in the member 20 to detachably secure the cable 24 to the lower jaw assembly 12 in good electrical connection therewith. As will be un-

2

derstood from Figures 2 and 3, it is intended that the cylinder 20 shall constitute a bearing for locating the lower jaw assembly in the handle 10, being snugly received therein and detachably retained as by a fastening screw 28 seated in an insulating insert 30 in the cylinder 20. Figure 5 shows more clearly the upper or secondary jaw assembly 32 which includes an angularly disposed bar of generally rectangular cross section and of a width proportioned to fit snugly and oscillate between the side walls 16 of the lower jaw assembly. At its rear end, the bar 32 has the screw threaded bore 34 vertically disposed while the front end terminates in a flat jaw 36 arranged in parallelism with and superimposed upon the lower jaw 18. The jaw 36 is recessed rearwardly and provides a transversely positioned notch or recess 38 for a purpose to become later apparent. It will be noted that when assembled, the member 32 and its bore 34 lie beyond the confines of the handle 10, the enlarged portion containing bore 34 being slidably received in a correspondingly enlarged portion 35 of the lower jaw assembly 12.

The lower and upper surfaces respectively of the lower and upper jaws 18 and 36 are provided with insulating coatings 40 and 42 respectively, which overhang the front ends of the jaws to provide an insulating shield therefor and are detachably retained as by screws 44, embedded in countersunk apertures and covered as by a plastic insulating material 46. As shown clearly in Figure 2, the coatings 40 and 42 overhang both front and side walls of the jaws 18 and 36. The adjacent surfaces of the jaws are preferably recessed, see Figures 3 and 6, to receive inserts 50 and 52, grooved as at 48 and preferably of copper bonded to the jaw assemblies 12 and 32, which latter are conveniently formed of an aluminum alloy metal cast or molded about the inserts. The inserts have lateral walls 54 (Figure 4) embracing the sides of the jaws, are axially grooved as at 58 to receive and clamp an electrode, not shown, and the insert 50 has its lateral walls 54 provided with inwardly turned anchoring ribs 56.

The bore 34 receives a threaded plug 60 constituting an adjustable spring seat for a purpose to be later set forth.

The upper jaw is oscillated relative to the lower jaw by a metallic lever 62, journaled between the side wall 16 of the lower jaw assembly, as by a pin 64 secured in transverse bores 66. The forward end of lever 62 has a wedge shaped nose 68 freely engageable in the notch 38, while the adjacent surface of the upper jaw assembly 32 is

rounded or cut away as at 70 to give clearance for the lower, rounded surface of lever 62. At its rear end, lever 62 is recessed at 74 to detachably receive a seat 76 which guides and seats a pair of concentric coil springs 78, compressed between said seat 76 and the above mentioned adjustable screw threaded seating plug 60. An appropriately shaped insulating handle 80 is secured upon the upper surface of lever 62 as by screws 82, embedded therein and covered by an insulating seal as at 84. Handle 80 has a depending skirt 86 adapted to surround the rear portion of the lever 62 and extending within the confines of handle 10 in a longitudinal slot 88, this skirt being proportioned to freely travel between the side walls 16 as the handle is depressed or released.

Substantially intermediate their lengths, the side walls 16 have lateral bosses 90, and screw threaded apertures 92, for attaching cylindrical insulating shield 94, which at the top portion is appropriately cut away to provide the slot or operating clearance 98 for handle 80. Insulating seals 96 are provided to overlie the head of the screws 100 which are preferably countersunk in the member 94.

From the foregoing, it is believed that the operation will be readily understood. The springs 78 yieldingly oscillate the lever 62 in a counter-clockwise direction about the pin 64, causing the nose 68 to bias notch 38 and consequently the upper jaw assembly 32 downwardly about its fulcrum point of contact with the enlarged portion 35. This motion normally closes the jaws and exerts a uniform and steady pressure, insuring an even and satisfactory electrical contact between an electrode and the groove seats 52 in the jaw assemblies. When it is desired to open the jaws, the handle 80 is depressed, thereby rotating the lever 62 in a clockwise direction against the action of springs 78 and elevating the upper jaw. The aluminum alloy construction of the jaw assemblies provides light weight with good strength and electrical conductivity while the copper jaw inserts give maximum current carrying capacity to the electrodes and minimizes the heating of the jaws by the heavy electric current. All external surfaces of the tool are full insulated to render the implement shock proof while the electrical conductor is secured directly to the main or lower jaw assembly for maximum electrical conductivity while the connection is housed in protected relation in the handle.

Since various embodiments of the invention will be readily apparent, I do not limit myself to the exact construction disclosed but may avail myself of all modifications falling within the scope of the appended claims.

I claim as my invention:

1. An electrode holder including a tubular handle, a main jaw assembly secured to said handle, an annular channel within the main jaw assembly, a secondary jaw assembly received within said main jaw assembly and an operating element for moving said secondary jaw assembly relative to the main jaw assembly, said secondary jaw assembly including a circular portion at its inner end slidably engaging said annular chamber and a flat jaw at its forward end having a transverse notch, said operating element

having a nose engaged in said notch for actuating said secondary jaw assembly.

2. An electrode holder including a tubular handle, a main jaw assembly secured to said handle, a secondary jaw assembly operative with and received within said main jaw assembly relative to the main jaw assembly, said secondary jaw assembly having an enlarged extremity, a bore in said extremity, a plug adjustable in said bore, spring means interposed between said plug and said operating element, said main jaw assembly being contoured to slidably receive said enlarged extremity.

3. An electrode holder including a tubular handle, a main jaw assembly secured to said handle, a secondary jaw assembly operative with and received within said main jaw assembly and an operating element for moving said secondary jaw assembly relative to the main jaw assembly, said main jaw assembly including parallel side walls for receiving said secondary jaw assembly therebetween and a laterally enlarged space between said side walls for receiving and journaling an enlarged extremity of said secondary jaw assembly.

4. An electrode holder including a handle, a fixed jaw assembly carried thereby, a movable jaw assembly received within said fixed jaw assembly, an operating element including a lever with arms of unequal length, a resilient means, the short arm engaging the movable jaw assembly intermediate its ends and the long arm being engaged with the resilient means to bias the jaw assemblies into closed position, said fixed jaw assembly including parallel side walls receiving said movable jaw assembly therebetween and a laterally enlarged space between said side walls for journaling an enlarged extremity of said movable jaw assembly.

5. An electrode holder including a handle, a main jaw assembly carried thereby, a secondary jaw assembly cooperating with and received within said main jaw assembly, an operating element, said secondary jaw assembly having an enlarged extremity, a bore in said extremity, a plug adjustable in said bore, spring means interposed between said plug and said operating element, said main jaw assembly being contoured to slidably receive said enlarged extremity, said operating element having a depending skirt enclosing the rear surface thereof.

HENRY J. WAGNER.
